UNITED STATES PATENT OFFICE.

DAVID E. ROSS AND JAMES D. HOFFMAN, OF LA FAYETTE, INDIANA, ASSIGNEES TO PURDUE UNIVERSITY, OF LA FAYETTE, INDIANA, A CORPORATION OF INDIANA.

VENTILATING SYSTEM.

Application filed March 1, 1923. Serial No. 622,093.

To all whom it may concern:

Be it known that we, DAVID E. ROSS and JAMES D. HOFFMAN, citizens of the United States, residing at La Fayette, in the county 5 of Tippecanoe and State of Indiana, have invented certain new and useful Improvements in Ventilating Systems; and we hereby declare that the following is a full, clear, and exact description thereof, reference being had to the accompanying drawings 10 which form part of this specification.

This invention is an improvement in ventilating systems for buildings, and is particularly intended for ventilating the class 15 rooms of schools, etc. The primary object of the invention is to insure real and adequate ventilating of a room by withdrawing the foul air about equally from the room at numerous points in the room, so the fresh 20 air can be circulated therein; and also to provide means whereby, if desired, fresh air can be forced into the room simultaneously with the withdrawal of the foul air.

Another object of the invention is to provide 25 a ventilating system which will not create objectionable air draughts on the students or persons occupying the room.

Except in very large rooms the forcible withdrawal of the foul air would suffice to 30 draw fresh air into the room through the fresh air ducts, or the forcible introduction of fresh air into the room would cause the expulsion of the foul air through the foul air ducts. In large rooms we prefer to both 35 forcibly withdraw foul air from the room and to forcibly inject fresh air into the room.

A further object of the invention is to provide 40 an apparatus which can be easily installed in class rooms already built without any expensive alterations therein, and without interference with the lighting or heating system installed therein; which can be made to enhance the architectural appearance of the room.

To enable others to adapt and use the invention we will explain it with reference 45 to the accompanying drawings, which diagrammatically illustrate a ventilating apparatus embodying the invention, and then summarize in the claims the essentials of the invention, combinations of parts, and novel features of construction, for all of which protection is desired.

In said drawings:

Fig. 1 is a diagrammatical perspective view of a portion of a class room with our novel ventilating apparatus installed therein.

Fig. 2 is a longitudinal sectional view through the ventilating apparatus installed 60 at one side of the room, and

Figs. 3, 4, 5, 6, and 7 are detail sectional views of the arrangement of the valves whereby the air may be drawn into or out 65 of either set of ducts.

In ordinary school rooms there are usually provided black-boards E on the side walls, the lower edges of such black-boards being about three feet above the floor level or wash board, indicated at 1 in the drawings, and likewise these black-boards E usually have a shallow rack or chalk shelf 1^a extending along the bottom thereof. We utilize the space below this shelf 1^a for an air duct A which air duct may be formed in 70 the form of a flattened tube, or applied to the wall so as to form such a tube, and which duct lies close to the side wall and beneath said shelf. The shelf 1^a might form the top of the air duct A and the side wall 75 3, the inside wall thereof, or, if desired, the top of the duct A may be formed by a narrow strip of material 2^a attached to the top of the front side 2 of the duct, and underlying the shelf 1^a. The bottom 2^b of this duct A may be formed by a narrow strip 80 of similar material, and the back 2^c of another strip of such material. The strips 2, 2^a, 2^b, 2^c, may be preformed if desired and attached to the wall in any suitable manner. 85

This duct A is intended to extend entirely along one or more sides of the room to be ventilated. Preferably we would extend it entirely around the room to be ventilated. The duct A communicates preferably at one 90 or more corners of the room, with an outlet duct or ducts B which may be conveniently formed of any suitable material and may be of any desired cross section, and extends out of the room to the fan casing 4, as shown in Fig. 1.

The cross sectional area of the duct B may approximate the cross sectional area of the duct A. The space below the chalk rail 95 2 extends nearer to or farther from the floor level. All of these ducts are preferably proportioned in size to suit the conditions of

the room and its seating capacity. The duct B extends to the outside or to a duct leading to the outside of the building through which the foul air in the room may be discharged.

In the duct A preferably in the bottom thereof, are formed a series of inlet openings α , and the total area of these inlet openings should approximately equal the cross sectional area of the duct B so that when suction is applied to the duct B by means of fan 4 to exhaust the air from the duct A, air will be drawn into duct A through all of the openings α . In order that this may be properly done the openings α should be of increasingly larger area, beginning with the opening nearest the duct B to those most remote therefrom, so as to insure that air will be drawn in equal amounts into the duct A from all parts of the room through all the openings α therein.

Air has even a greater tendency than water to cross-current and if the openings α were all of the same area more air would be drawn through the openings α nearest the duct B or point of suction pressure than through the openings α more remote therefrom, and there would be more foul air withdrawn from the room through the openings adjacent the duct B than through the openings remote therefrom.

In some cases, particularly in very large rooms, in order to further prevent unequal withdrawal of foul air into the duct A, the duct A may be divided into a plurality of smaller ducts A' by means of partitions or vanes 2^v which may be arranged within the duct as indicated in Fig. 2, each sub-duct A' conducting air from one or more of the openings α into the duct B.

The duct B is provided with, or connects with, a suitable suction device such as an electrically operated fan 4 by which the foul air can be withdrawn through duct B and expelled to a suitable point of discharge. As shown, the duct B communicates with the inlet of a fan casing 4 and the outlet of the fan casing connects by a pipe 4^a with the discharge outlet not shown. This fan may be of any suitable construction, and is preferably electrical, but might be mechanical, and is merely diagrammatically illustrated in the drawings.

To further increase the ventilation we preferably provide an air duct C, formed of any suitable material, and fitted like a moulding around the upper corners of the room. This duct C may be formed of metal or other tubing of the same material as duct A and may be suitably secured in position to form the air duct C. Duct C communicates with a duct D preferably adjacent the duct B, communicating with the exterior atmosphere through a suitable flue or conduit 5^a. Duct D is also preferably provided with a

fan 5, which may be similar to the fan 4, but so arranged as to force fresh air from the exterior of the building through the duct D and into the duct C.

The duct C is provided preferably in its front vertical face with a series of openings c , which are preferably of such area that the total area of these openings c will approximately equal the cross sectional area of the duct C; and the area of the duct C should correspond to, or be slightly greater than the duct D, so that the air forced into the duct D will be evenly distributed through these openings c in all parts of the room.

The air inlet openings c are preferably arranged like the air outlet openings α , the openings c gradually increasing in area from the opening nearest the pipe D to the opening furthest removed therefrom, so that the fresh air will be uniformly distributed throughout the room, at all points, in the same way that the foul air will be uniformly withdrawn from the room.

If desired, to provide for contingencies or repairs, the ducts B and D might be arranged to run side by side for a short distance at some convenient point and have a common intermediate wall, as indicated in Figs. 3 to 7 inclusive, the intermediate wall being provided with adjacent openings closable by valves 7, 8. These valves can be swung to the right or left to close either duct B or D. If it should be desired to withdraw air from both ducts A and C, the valve 7 might be turned to the position indicated in Fig. 5, with valve 8 in vertical position, and then the air from both ducts B and D would be drawn out through and by means of fan 4. If the duct A should be undergoing repair, valves 7 and 8 could be turned to the positions indicated in Fig. 3, and air would then be drawn out through duct C. If for any reason it should be desired to force fresh air through both ducts A and C, these valves 7 and 8 could be adjusted to the positions shown in Fig. 6; and the fresh air would then be forced by fan 5 into the room through both ducts A and C. If valves 7 and 8 should be also adjusted to the positions indicated in Fig. 4, then fresh air would be forced into the room only through the duct A. This could be done in case duct C was being repaired. When valves 7 and 8 are both in the vertical positions, as shown in Fig. 7, then ducts B and C act independently.

As stated, the drawings are merely diagrammatic but from the foregoing description and explanation it will be understood that our invention provides ample ventilation, for removal of foul air uniformly from a room preferably adjacent the floor level, or if desired at both floor and top level. Preferably, in large rooms, the foul air is removed from the floor level and fresh air simultaneously.

ously forced in the room at the top level. The foul air is drawn from the room practically uniformly and without creating any undesirable draught; and the fresh air can 5 be introduced in the room uniformly without creating any undesirable draughts.

During the hot summer months, withdrawing warm air from the ceiling of the room through duct C will cool the room 10 more effectively than by withdrawing air from the floor of the room through duct A, hence in hot weather the valves 7 and 8 should be adjusted as indicated in Fig. 3. However, in cold weather the valves 7 and 15 8 should be adjusted as shown in Figs. 5 or 7, preferably the latter, so that foul air may be withdrawn from the floor of the room.

What we claim is:

1. In ventilating apparatus for school 20 rooms and the like; a duct having a series of openings increasing in area as they are further removed from the outlet of the duct, the total area of the series of openings in the duct approximating the cross sectional area 25 of the outlet, and a series of partitions within the main duct forming sub-ducts therein, substantially as described.

2. In a ventilating apparatus for school 30 rooms and the like; a duct arranged along- side the wall of the room adjacent the floor and having a series of openings in its lower side increasing in area as they are further removed from the outlet of the duct, the total area of the series of openings in the 35 duct approximating the cross sectional area of the outlet, means for withdrawing air from the duct, and a series of partitions within the duct forming sub-ducts therein, substantially as described.

40 3. In combination with ventilating apparatus as set forth in claim 2, a second air duct arranged along the wall adjacent the ceiling and having a series of openings in one face, the total area of the openings approximating the cross sectional area of the inlet of the second air duct, and means for 45 forcing air into said duct.

4. In combination with ventilating apparatus as set forth in claim 2, a second air 50 duct arranged adjacent the ceiling and having a series of openings in one face increasing in area as they are further removed from the inlet of the duct, the total area of the series of openings in said duct approximating the cross sectional area of the inlet thereof, and means for forcing air into said duct; whereby air may be admitted into the room simultaneously with the withdrawal of air therefrom.

60 5. In combination with ventilating apparatus as set forth in claim 2, a second air duct arranged adjacent the ceiling and having a series of openings in one face increasing in area as they are further removed 65 from the inlet of the duct, the total area of

the series of openings in said duct approximating the cross sectional area of the inlet thereof, and means for forcing air into said duct; whereby air may be admitted into the room simultaneously with the withdrawal 70 of air therefrom, the inlet and outlet ducts having communicating openings and valves for closing or opening said openings whereby by properly adjusting said valves air may be forced into the room through the 75 outlet duct or both ducts; or air may be forced into the room through the inlet duct or both ducts, substantially as described.

6. In a ventilating system for school rooms and the like, a narrow wide horizontally disposed duct arranged alongside the wall adjacent the floor and having a series of openings in its lower side increasing in area from a point adjacent the outlet of the duct as they are further removed from the outlet; a second vertical duct communicating with the outlet of the horizontal duct, and a fan for withdrawing air from the vertical duct, the total area of the openings in the horizontal duct approximating the cross 85 sectional area of the vertical duct, substantially as described.

7. Ventilating apparatus as set forth in claim 6 having a series of partitions forming sub-ducts within the horizontal duct, 90 substantially as described.

8. In combination with ventilating apparatus as set forth in claim 6, a second horizontal duct arranged adjacent the ceiling and having a series of openings in one face gradually increasing in area as they are further removed from the inlet of said duct; a second vertical duct communicating with the inlet of the second horizontal duct; and a fan for forcing air through said second vertical duct into the upper air duct; whereby air may be admitted into the room simultaneously with the withdrawal of air therefrom.

9. In a ventilating system for school 100 rooms and the like, a horizontally disposed duct arranged alongside the wall adjacent the floor and having a series of openings in its lower side, a vertical duct communicating with the outlet of the horizontal duct, and a fan for withdrawing air from the vertical duct, the total area of the openings in the horizontal duct approximating the cross sectional area of the vertical duct; a second horizontal duct arranged adjacent 105

the ceiling and having a series of openings in one face, a second vertical duct communicating with the inlet of the second horizontal duct; means for forcing air through said second vertical duct into the upper air duct; whereby air may be admitted into the room simultaneously with the withdrawal of air therefrom, the vertical ducts having communicating openings and valves for closing 110 or opening said openings; whereby by ad-

justing said valves air may be forced into the room through either or both horizontal ducts; or air may be withdrawn from the room through either or both horizontal ducts, substantially as described.

10. In a ventilating system for school rooms and the like, a narrow wide horizontally disposed duct arranged alongside the wall adjacent the floor and having a series of openings in its lower side increasing in area as they are further removed from the outlet of the duct; a vertical duct communicating with the outlet of the horizontal duct; and a fan for withdrawing air from the vertical duct, the total area of the openings in the horizontal duct approximating the cross sectional area of the vertical duct; a second horizontal duct arranged adjacent the ceiling and having a series of openings in one face increasing in area as they are

further removed from the inlet of said duct; a second vertical duct communicating with the inlet of the second horizontal duct; and a fan for forcing air through said second vertical duct into the upper air duct; whereby air may be admitted into the room simultaneously with the withdrawal of air therefrom; the vertical inlet and outlet ducts having adjacent portions with communicating openings, and valves for closing or opening said openings; whereby by adjusting said valves air may be forced into the room through either or both horizontal ducts, or air may be withdrawn from the room through either or both horizontal ducts, substantially as described.

In testimony that we claim the foregoing as our own, we affix our signatures.

DAVID E. ROSS.
JAMES D. HOFFMAN.
